UNITED STATES PATENT OFFICE.

WILLIAM A. TWINING, OF CLEVELAND, OHIO, ASSIGNOR TO WILLIAM E. DONNELLY, OF CLEVELAND, OHIO.

FRUIT-JAR WRENCH.

SPECIFICATION forming part of Letters Patent No. 755,081, dated March 22, 1904.

Application filed January 26, 1903. Serial No. 140,495. (No model.)

To all whom it may concern:

Be it known that I, WILLIAM A. TWINING, a citizen of the United States, residing at Cleveland, in the county of Cuyahoga and State of Ohio, have invented certain new and useful Improvements in Fruit-Jar Wrenches; and I do hereby declare the following to be a full, clear, and exact description of the invention, such as will enable others skilled in the art to which it pertains to make and use the same.

My invention relates to wrenches especially adapted for screwing caps on and off from fruit-jars, and has for its object simplicity and economy of construction and strength and effectiveness in operation, also adaptability to different-size covers.

My invention consists in the peculiar construction of the wrench and assemblage of parts, all of which will be hereinafter fully set forth and claimed.

In the drawings, Figure I is a view in isometric, illustrating a wrench constructed according to my invention, showing the same as applied to a fruit-jar cap and in position for screwing the cap on the jar. Fig. II is a plan view illustrating the position in solid and dotted lines of the wrench and its parts when the same is applied and adjusted for opening or closing the cap. Fig. III is a plan view illustrating how my wrench may be utilized for a cover of larger diameter than that illustrated in Fig. II.

A represents a lever which is pivotally attached to an embracing ring B. This embracing ring is oblong and is formed of plate metal of sufficient width and thickness to stand the necessary strain. The inner contour of the ring B, as at B', from the point b to the point b' is curved so as to embrace snugly a cap or cover which is to be operated upon, and as its opposite portion, as at B², from the point b to b' is formed of such curvature as to act as a cam for adjusting to position a pivoted curved engaging jaw C, this jaw C being in turn pivotally secured, as at c, to the inner end of the pivoted lever A and being formed with a concave inner portion c', which is adapted to the curvature of a cap in such a way as to embrace it snugly. The opposite edge of the jaw

C is of such curvature as to engage the side 50 b² b³ of the ring B, whereby as the lever A is swung from one side to the other the jaw C will adjust itself to such position as to allow the wrench to be placed over a cap and be adjusted thereto for the purpose of turning the same in one direction or the other, as the case may be, and this feature forms a more or less important element of my invention, inasmuch as were the jaw C free from contact with other parts of the mechanism in its shifting from 55 one part to the other without altering its position in relation to the lever A it would be in the way, and the wrench could not readily be placed upon the cap without utilizing both 60 hands of the operator or manipulator.

The operation of my wrench can be easily understood from an examination of the drawings in connection with the above description, it being only necessary to state that as it is desired to screw down or unscrew the cap the 70 lever A is shifted to either position, as illustrated in Fig. II, when the jaw C will adjust itself by contact with the inner portion of the ring B to proper position, so that the wrench will receive the cap, and then by turning the 75 handle in an opposite direction the cap may be screwed down or unscrewed through the engagement of the jaw C, which hugs the cap snugly between its concave portion c' and the portion b b' of the embracing-ring B.

By forming the ring B of more or less "greater diameter" the wrench can be made so as to adapt itself to varying diameters of caps or covers.

Another important feature of this invention is economy in construction and assemblage, because in forming the parts the ring B and jaw C can be stamped out of one and the same piece of material or blank, and the jaw C can be formed from the same die and 90 at the same time as the forming of the ring D. It being struck from the middle portion of the blank, also all the pivot-holes may be formed at this operation, and in assembling the parts it is only necessary to place them in 95 proper juxtaposition, pass suitable rivets through the holes, and with a single blow or two of the hammer or machine the wrench is

complete, no subsequent manipulation being necessary.

I do not wish to be limited in this invention to the exact assemblage and contours of parts 5 or to the exact structural features, inasmuch as they may be modified and still be included in the scope of this invention.

What I claim is—

A jar-wrench comprising a solid ring lying 10 in a straight plane throughout its length, said ring having its inner face to one side of its center formed with oppositely-disposed curved cut-out portions, a lever pivoted to one face of said ring intermediate the cut-out portions

thereof, and a jaw having a curved outer face 15 pivoted to the under face of the inner end of said lever whereby it will lie within said ring, the curved face of said jaw being adapted for engagement with the curved walls of the cut-out portions of said ring substantially as and 20 for the purpose specified.

Signed at Cleveland, in the county of Cuyahoga and State of Ohio, this 24th day of July, 1902.

WILLIAM A. TWINING.
